United States Patent Office

Des. 203,367

Patented Dec. 28, 1965

203,367

DISPLAY CABINET FOR KNIVES AND THE LIKE

Sidney S. Wisch, Shaker Heights, Ohio, assignor to Cole National Corporation, Cleveland, Ohio, a corporation of Ohio

Filed Oct. 2, 1964, Ser. No. 81,999

Term of patent 14 years

(Cl. D80—11)

Fig. 1

Fig. 2

Fig. 3

Fig. 5

Fig. 6

FIG. 1 is a top plan view of a display cabinet for knives and the like embodying my new design;

FIG. 2 is a front elevational view thereof;

FIG. 3 is a bottom plan view thereof;

FIG. 4 is a rear elevational view thereof;

FIG. 5 is an elevational view taken from the right side thereof; and

FIG. 6 is an elevational view taken from the left side thereof.

I claim:

The ornamental design for a display cabinet for knives and the like, substantially as shown.
